ELECTROSTATIC PRECIPITATOR

Ray W. Warburton, Medfield, Mass., assignor to
Westinghouse Electric Corporation, East Pitts-
burgh, Pa., a corporation of Pennsylvania

Application June 29, 1949, Serial No. 101,947

17 Claims. (Cl. 183—7)

1

This invention relates to electrostatic precipitators for removing small foreign particles from fluids.

The usual electrostatic precipitator used for removing small foreign particles such as dust, from gases such as air, contains closely spaced, metal collector plates to which electrostatically charged dust particles are attracted. A disadvantage of such a construction is that when the collector plates are loaded with collected matter, they are difficult to clean.

This invention avoids the necessity for cleaning collector electrodes by constructing the collector electrodes of material which is so inexpensive that it is economical to remove and discard them when they are loaded with collected foreign matter.

A feature of the invention is that the collector electrodes are assembled as a collector cell which is easily removed and replaced in an electrostatic precipitator.

Another feature of the invention is that the electrical connections to the high voltage, direct current, power supply are automatically completed when the collector cell is inserted into its working position in its associated electrostatic precipitator.

An object of the invention is to reduce the manufacturing cost of electrostatic precipitators.

Another object of the invention is to reduce the maintenance cost of electrostatic precipitators.

Another object of the invention is to overcome the necessity for cleaning the collector electrodes of electrostatic precipitators.

Another object of the invention is to provide an inexpensive disposable, collector electrode assembly for an electrostatic precipitator.

The invention will now be described with reference to the drawing, of which:

Fig. 1 is a side elevation, partially in section, of an electrostatic precipitator embodying this invention;

Fig. 2 is a projected view, partially exploded, of a portion of the collector electrode assembly of Fig. 1;

Fig. 3 is a plan view of one of the grounded discs of the collector electrode assembly;

Fig. 4 is a plan view of one of the collector electrode stampings of the collector electrode assembly;

Fig. 5 is a plan view of one of the spacers used in the collector electrode assembly, and

Fig. 6 is a plan view of one of the discs used in the collector electrode assembly for making

2

electrical contact with the charged, centrally extending rod of the assembly.

This invention utilizes electrode members of semi-conductive material for the collector electrodes of an electrostatic precipitator, the members having stamped or crimped portions for providing extended fluid contacting surface. The members are stacked, and are electrically interconnected, the opposed electrode surfaces of adjacent members having voltages thereon which are provided by voltage drops caused by current flow through the members whereby electrostatic fields between the opposed surfaces are established.

Referring now to Fig. 1 of the drawing, a cylindrical metal casing 5 has an open upper end on which is fitted the metal cover 6 which has a gas inlet 7 of reduced diameter centrally in its upper end. The lower portion of the casing is formed as a cylinder of reduced diameter and has the gas outlet 8 in its lower end.

The rods 9 extend cross-wise the interior of the cover 6 and are attached at their ends to its inner surface. They extend through the upper portion of the electric insulator 10 and support same from the cover.

The metal rod 11 is attached to the insulator 10 and extends along the longitudinal axis of the casing 5. The very thin, metal disc 12 is clamped between the clamping discs 13 just below the insulator 10. The disc 12 has sharp edges which are spaced from the interior surface of the casing 5 and, forms an ionizer electrode as will be described in the following.

Attached to the rod 11 at equally spaced intervals are the electrode discs 15 which have the central openings 16 therein between which extend the disc portions 17 which contain the circular central openings 18 having slightly smaller diameters than the diameter of the rod whereby they may be force-fitted thereon.

The uppermost disc 15 is spaced from the lower disc 13 by the collar 19, and it may have the sleeve 20 attached to its upper portion, and which may have threaded therein the screw 21 extending through the rod 11 for securely fastening the uppermost disc 15 to the rod for a purpose to be described in the following.

Arranged centrally between adjacent electrode discs 15 are the discs 22 which have the central openings 23 which are placed centrally around the rod 11, and which have the extensions 24 which contact the interior surface of the casing 5. Arranged between each disc 15 and an adjacent disc 22 are, in the embodiment of the invention

illustrated by the drawing, three electrode members 25 separated from each other by the spacer discs 26 which have the central openings 27a therein.

The electrode members 25 are circular and have the central circular openings 27 therein. They have the flat portions 28 extending in planes perpendicular to the rod 11 with radially extending edges; have the flat portions 29 extending perpendicular to the portions 28 at the radially extending edges thereof, and have the flat portions 30 extending between the portions 29 at points equally spaced from the flat portions 28. The members 25 may be stamped from flat sheets or may be molded or cast in the shape illustrated or other desired shapes providing the same extended surface function.

The electrode discs 15, 22 and 26 and the electrode members 25 are formed from semi-conductive material, or said in another way, of material having a relatively high electrical resistance. This material may be stiff cardboard containing dispersed metallic salts or particles, or may be a urea or other synthetic plastic. It may be a non-conductor, coated with a semi-conductive material such as a thin layer of high resistance carbon.

The lowermost disc 40 is a circular disc having a central opening 41 and has a sharp outer edge which contacts the inner surface of the casing 5.

The lower end of the rod 11 is terminated in a plug which is fitted into a socket formed by the inwardly biased strips 32 of spring metal attached to the upper surface of the insulator 33 which is attached to the interior of the lower portion of the casing 5 by the spaced arms 36. The socket strips 32 are electrically connected to the wire 34 which extends through the grommet 35 fitted in an opening in a wall of the casing, to a terminal, which may be a +12,000 volt terminal, of a suitable high voltage, direct current, supply source which is not illustrated, and the negative terminal of which may be grounded and connected to the casing 5 of the precipitator.

The discs 15, 22, 26 and 40 and the electrode members 25 are assembled by cementing their contacting surfaces together following which they are placed on the rod in the position illustrated by the drawing, the crew 21 then being inserted and tightened. This secures the electrode assembly securely to the rod. The rod with the attached electrode assembly is then inserted in the casing 5 as illustrated by Fig. 1 of the drawing, the plug end of the rod automatically being connected electrically to the high voltage supply wire 34 when it is in position, and the extensions 24 of the discs 22 automatically making contact with the interior surface of the casing.

The spacings between portions of the electrode members 25 and the electrode discs 15, 22 and 24 which they contact, provided by the perpendicular portions 29 thereof, form gas passages each bounded as best illustrated by Fig. 1, and the lower portion of Fig. 2, by two pairs of opposed walls provided by surfaces of the electrode members 25 and by the discs. These passages connect at their inlets formed at their outer edges, with the gas inlet passage extending from the gas inlet 7 around the discs and the electrode members and between the outer edges of same and the interior surface of the casing 5, and connect at their inner edges with the central gas outlet passage aligned with the openings 16, 23 and 27a in the discs, the open-

ings 21 in the electrode members 25, and the outlet 8. The gas flow through all of the gas passages is indicated by the arrows of Fig. 1 of the drawing.

In operation, the gas entering the inlet 7 is ionized by the electrostatic field between the sharp edges of the disc 12 and the adjacent inner surface of the casing 5, whereby the foreign particles entrained therein are given positive electrostatic charges.

Electric current flows between the discs 15 which contact the positively charged rod 11, and between the discs 22, the extensions 24 of which contact the grounded casing 5, in paths which include the discs 15, the electrode members 25, and the discs 22 and 26. This current flow produces voltage drops in these paths, which establish voltages along different points along the paths which vary between 12,000 and zero volts depending upon their positions. Thus the opposed boundary walls of the horizontal gas passages illustrated by Fig. 1 of the drawing, have different potentials thereon which result in electrostatic fields therebetween, these fields causing the electrostatically charged dust particles passing through the horizontal gas passages to be deposited upon the charged walls thereof.

When the collector cell has become loaded with collected matter, it is a simple matter to remove the cover 6 from the casing 5 and to pull-out the collector cell assembly attached to the rod 11. The screw 21 can then be loosened and the cell assembly removed and replaced by a previously assembled clean one.

When the collector cell assembly is removed from the casing 5, the sharp edge of the lowermost disc 40 scrapes the inner surface of the casing thus removing the collected matter adhering thereto.

The collector could be used for cleaning liquids in which case the ionizer disc would be omitted.

While one embodiment of the invention has been described for the purpose of illustration, it should be understood that the invention is not limited to the exact apparatus and arrangement of apparatus illustrated, and described, since modifications therefrom may be suggested by those skilled in the art, without departure from the essence of the invention.

What is claimed, is:

1. A collector cell for an electrostatic precipitator comprising a plurality of spaced, aligned, parallel, collector electrodes having surfaces of electrically semi-conductive material, said electrodes having central, aligned, gas flow openings therein, a rod or tube like member of electrically conductive material extending centrally through said openings, means attaching one of said electrodes to said member, and means attaching other of said electrodes to said one electrode.

2. A collector cell for an electrostatic precipitator comprising a plurality of spaced, aligned, parallel, collector electrodes having surfaces of electrically, semi-conductive material, means electrically connecting said electrodes together, said electrodes having central, aligned, gas flow openings therein, a rod or tube like member of electrically conductive material extending centrally through said openings, means including said member for applying an electrical charge of one polarity to one of said electrodes, and means for applying an electrical charge of the opposite polarity to another of said electrodes.

3. A collector cell for an electrostatic precipitator comprising a plurality of spaced, aligned,

parallel, collector electrodes having surfaces of electrically, semi-conductive material, said electrodes having central, aligned, gas flow openings therein, a rod or tube like member of electrically conductive material extending centrally through said openings, means attaching one of said electrodes to said member, means attaching others of said electrodes to said one electrode, means for applying an electrical charge of one polarity to said member, and means for applying an electrical charge of the opposite polarity to one of said others of said electrodes.

4. A collector electrode for an electrostatic precipitator having surfaces of electrically semi-conductive material and having a central gas flow opening therein, said electrode having a first plurality of surfaces spaced apart around said opening in one plane, and having a second plurality of surfaces spaced apart around said opening in another plane parallel to said plane, the said surfaces of said second plurality being aligned with the spaces between the said surfaces of said first plurality, said electrode having surfaces perpendicular to said planes extending between said surfaces of said first and second pluralities.

5. A collector cell for an electrostatic precipitator comprising a plurality of spaced, parallel electrodes having surfaces of electrically, semi-conductive material and having aligned, central, gas flow openings therein, a rod or tube like member of electrically conductive material extending centrally through said openings, and means for assembling said electrodes to each other and to said member.

6. An electrostatic precipitator comprising a casing, a plurality of spaced, parallel electrodes having surfaces of electrically, semi-conductive material, in said casing, said electrodes having central, fluid flow openings therein and having outer edges spaced from the interior of said casing, a rod or tube like member of electrically conductive material extending centrally through said openings, means insulatedly supporting one end of said rod from said casing, means attaching one of the outer of said electrodes to said member, means attaching the others of said electrodes to each other and to said one electrode, the other outer electrode having an extension contacting the interior of said casing, and means for applying electrical charges of opposite polarities to said member and to said casing.

7. An electrostatic precipitator comprising a casing having a gas inlet, a plurality of spaced, parallel collector electrodes having surfaces of electrically, semi-conductive material, in said casing, said electrodes having central, gas flow openings therein and having outer edges spaced from the interior of said casing, a rod or tube like member of electrically conductive material extending centrally through said openings, means insulatedly supporting said member from said casing, means attaching one of the outer of said electrodes to said member, means attaching the others of said electrodes to each other and to said one electrode, the other outer electrode having an extension contacting the interior of the casing, means for applying electrical charges of opposite polarities to said member and casing, and an ionizer electrode connected to said member adjacent said inlet, said ionizer electrode having sharp edges spaced from the interior of said casing.

8. An electrostatic precipitator comprising a casing having a fluid inlet, said inlet having a

removable cover therearound, a plurality of spaced, parallel collector electrodes having surfaces of electrically, semi-conductive material, in said casing, said electrodes having central, fluid flow openings therein and having outer edges spaced from the interior of said casing, a rod or tube like member extending centrally through said openings, means attaching one of the outer of said electrodes to said member, means for attaching the others of said electrodes to each other and to said one electrode, the other outer electrode having an extension contacting said casing, means insulatedly supporting said member from said cover, and means for applying electrical charges of opposite polarity to said member and casing.

9. An electrostatic precipitator as claimed in claim 8 in which the means for applying an electrical charge to said member includes a socket or jack like member into which the end of the first mentioned member opposite said cover is fitted and which is insulatedly supported from said casing.

10. An electrostatic precipitator comprising a casing having a gas inlet and a gas outlet, said casing having a removable cover around said inlet, a plurality of spaced, parallel collector electrodes having surfaces of electrically conductive material, in said casing, said electrodes having central, gas flow openings therein and having outer edges spaced from the interior of said casing, a rod or tube like member extending centrally through said openings and having one end adjacent said inlet and having its other end adjacent said outlet, means attaching one of the outer of said electrodes to said member, means attaching the others of said electrodes to each other and to said one electrode, the other outer electrode having an extension contacting said casing, means insulatedly supporting said one end of said member from said cover, a socket or jack of electrically conductive material removably supporting said other end of said member and insulatedly supported from said casing, means for applying electrical charges of opposite polarity to said member and said casing, and an ionizer electrode connected to said member between said inlet and said electrodes, said ionizer electrode having sharp edges spaced from the interior of said casing.

11. A collector cell as claimed in claim 1 in which each of a plurality of the electrodes has surfaces extending in spaced parallel planes perpendicular to said member, and has other surfaces extending perpendicular to said planes.

12. A collector cell as claimed in claim 2 in which each of a plurality of the electrodes has surfaces extending in spaced parallel planes perpendicular to said member, and has other surfaces extending perpendicular to said planes.

13. A collector cell as claimed in claim 3 in which each of a plurality of the electrodes has surfaces extending in spaced parallel planes perpendicular to said member, and has other surfaces extending perpendicular to said planes.

14. An electrostatic precipitator as claimed in claim 6 in which each of a plurality of the electrodes has surfaces extending in spaced parallel planes perpendicular to said member, and has other surfaces extending perpendicular to said planes.

15. An electrostatic precipitator as claimed in claim 7 in which each of a plurality of the electrodes has surfaces extending in spaced parallel planes perpendicular to said member, and has

other surfaces extending perpendicular to said planes.

16. An electrostatic precipitator as claimed in claim 8 in which each of a plurality of the electrodes has surfaces extending in spaced parallel planes perpendicular to said member, and has other surfaces extending perpendicular to said planes.

17. An electrostatic precipitator as claimed in claim 10 in which each of a plurality of the collector electrodes has surfaces extending in spaced parallel planes perpendicular to said member,

and has other surfaces extending perpendicular to said planes.
